UNITED STATES PATENT OFFICE.

JOSEPH E. WHITFIELD, OF EAST PITTSBURGH, PENNSYLVANIA, ASSIGNOR OF ONE-HALF TO HENNING ALBERT JOHNSON, OF PITTSBURGH, PENNSYLVANIA.

INTERNAL-COMBUSTION ENGINE.

Application filed June 18, 1926. Serial No. 116,765.

More particularly my present invention relates to internal combustion engines of the type wherein the cylinder, or each of the cylinders, is provided with a single sleeve valve 5 to which is imparted both a reciprocating and an oscillating movement.

My improved sleeve valve is arranged to move in the same direction with the piston during the reciprocation of the latter, but 10 has only approximately one-half the stroke of the piston, and the oscillating motion of the sleeve valve is so timed that no material oscillating motion thereof occurs during the compression and power strokes of the piston, 15 while during the scavenging and intake strokes of the piston the valve is oscillated to bring the scavenging ports and the inlet ports, respectively, into registration.

In the preferred embodiment of my invention the sleeve valve is provided with a double seal, as is also the piston, thereby preventing leakage of fuel from the firing chamber and the entrance of lubricating oil into the firing chamber.

25 The sleeve valve is also water cooled both from within and without, as is also the piston during half of its stroke, thereby preventing excessive heat.

The firing chamber which extends into the 30 cylinder and is surrounded by the sleeve valve is also water cooled.

The firing chamber is of frustro-conical shape, expanding inwardly towards the piston, and the spark plug is positioned axially 35 of the firing chamber, thus assuring improved combustion.

Other novel features of construction, and also of arrangement of parts, will appear from the following description.

40 In the accompanying drawings wherein I have illustrated the best embodiment of the principles of my invention now known to me, Fig. 1 is a longitudinal section taken on a vertical plane of a four cylinder internal combustion engine of the four cycle type;

Fig. 2 is a cross section of the same taken on the line II—II in Fig. 1; Fig. 3 is a horizontal section taken on the line III—III in Fig. 1, the position of the sleeve valve therein illustrated being such as is assumed when the crank shaft is turned ninety degrees from its position shown in Fig. 1, and also showing the fuel and exhaust manifolds which

are omitted from Fig. 2; Fig. 4 is a side elevation showing one of the sleeve valves; Fig. 5 is a graphic diagram showing the approximate path of movement of the sleeve valve; Figs. 6 and 7 are sectional views of the cylinder and its associated parts, similar to Fig. 2 but showing modified forms, and Fig. 8 is a cross-sectional view of one of the cylinders showing the sleeve valve provided with a single port which is brought in turn in registration with the fuel inlet and exhaust ports.

55 Referring first to Figs. 1 to 4 inclusive, 1, 2, 3 and 4 represent the four cylinders of a four cycle internal combustion engine, said cylinders being shown cast en bloc.

50 It is of course evident that my invention 70 may be applied to a single cylinder engine or one of any number of cylinders and that said cylinders may be cast as separate units if desired.

55 5 represents the crank case upon which 75 said cylinders are superimposed in the usual manner, and 6 represents the usual water jacket surrounding the cylinders and connected with the usual water circulation system.

60 7 represents the cylinder heads, which in the case of cylinders cast en bloc, may also be an integral casting for all of the cylinders. The head of each cylinder is provided with a portion 8 depending into the cylinder and 85 provided with a threaded port 9 which is axially located and into which is screwed the spark plug 10 which thus extends axially into a firing chamber 11 of frustro-conical shape 90 expanding downwardly and formed in the extension 8 of the head 7. The water chamber 12 of the head surrounds the firing chamber 11, and 13 represents the water outlet, a suitable inlet being provided in the usual manner.

95 14 is a cylindrical sleeve valve which has a sliding fit within the cylinder wall and around the portion 8 of the cylinder head.

For convenience in construction the sleeve 100 valve 14 is provided with a cylindrical liner 15 fixedly attached which extends down below the firing chamber 11, and 16 is an annular space between the lower portion of the liner 15 and the sleeve valve 14 in which the skirt 17 of the inverted piston 18 has 105 a sliding fit. 18a represents a packing ring

or rings interposed between the piston and the liner.

The space 16 is of sufficient length to prevent the skirt of the piston being withdrawn therefrom during the operation of the engine.

The piston 18 is connected by the connecting rod 19 to the crank 20 of the main crank shaft 21. Alongside of each crank 20 is a 10 parallel crank 22 on the crank shaft 21, the crank 22 having approximately half the throw of the crank 20. 23 is a connecting rod attached to the crank 22 and having its other end provided with an elongated wrist 15 pin 24 which rotates and slides in a central bearing hole 25 of a swivel block 26. The block 26 is mounted in a box frame 27 fixed to or cast integral with the lower end of the sleeve valve 14 and the upper and lower 20 ends of the block 26 are provided with trunnions 28 which are journaled in bearing holes in said frame. Thus the block swivels on an axis parallel to the longitudinal axis of the sleeve valve. 29 is a second crank 25 shaft journaled parallel with the main crank shaft 21 and driven at one-half the speed of the crank shaft 21 as by means of the sprockets 30 and 31 and chain 32. The shaft 29 is provided for each cylinder with a 30 crank 33 and to each of said cranks is attached a connecting rod 34 whose other end is pivotally connected as at 35 to the corresponding connecting rod 23.

It is evident that the rotation of the 35 shafts 21 and 29 results in reciprocating and oscillating the sleeve valve 14, the function of the connecting rod 34 being to impart an intermittent oscillating movement of the sleeve valve, first in one direction and then 40 in the other direction, the swiveling of the block 26 and the longitudinal movement of the wrist pin 24 in its bearing 25 permitting the sleeve valve to be oscillated without binding.

45 In the embodiment of my invention shown in Figs. 1 to 4 inclusive each of the cylinders is provided with one or more exhaust ports 36 leading from the upper portion of the firing chamber 11 through the water jackets and connected with the exhaust manifold 37 as shown in Fig. 3. Also each 50 of the cylinders is provided with one or more fuel intake ports 38 leading from the firing chamber 11 through the water jackets 55 and connected to the fuel manifold 39.

Each of the sleeve valves 14 is provided with longitudinally elongated ports 40 and 41, the port 40 being arranged to be brought into registration with the exhaust port 36 of the cylinder by the proper oscillating movement of the sleeve valve, while the port 41 is likewise arranged to be brought into registration with the fuel inlet port 38 of the cylinder by a proper oscillation of the 60 sleeve valve. The ports 40 and 41 are ap-

proximately twice the length of the exhaust and inlet ports 36 and 38. The ports in the sleeve valve are equal in number to the exhaust port or ports and the intake port or ports of the cylinder.

The ports 36 and 38 are preferably diametrically opposed for convenient connection to the manifolds, while the ports 40 and 41 may be approximately ninety degrees apart.

The relative locations of the ports 36 and 38 and of the ports 40 and 41 are of course dependent on the length of the arc of the oscillating movement of the sleeve valve and may be varied accordingly.

The parts are assembled in such a manner that during the inward stroke of the sleeve valve which is simultaneous with the inward compression stroke of the piston and also during the outward stroke of the sleeve valve which is simultaneous with the outward firing stroke of the piston there is no material oscillating movement of the sleeve valve, while during the inward stroke of the sleeve valve which is simultaneous with the scavenging stroke of the piston the port 40 moves into and maintains registration with the exhaust port 36, and likewise during the next outward stroke of the sleeve valve which is simultaneous with the outward suction stroke of the piston the port 41 of the sleeve valve is brought into and maintained in registration with the port 38 of the cylinder, such registrations being effected by a rapid oscillation of the sleeve valve at the beginning of the stroke of the same so that the full port area is effective during substantially the entire stroke.

The movement of the oscillating sleeve valve is graphically illustrated in Fig. 5 105 wherein the reference letters *c*—*c'* at the upper and lower ends of the vertical dotted line indicate the top and bottom dead centers of the sleeve valve. The sleeve valve, whose movement is indicated by the arcuate 110 line, is assumed to turn clockwise. The reference letter *a* indicates the point at which the intake port 41 of the sleeve valve begins to move into registration with the intake port 38 of the cylinder, this point being 115 approximately fifteen degrees past top dead center, and as indicated by the curvature of the arcuate line, the oscillating motion is rapid to bring said ports quickly into complete registration. Such registration is maintained substantially full until the sleeve valve passes bottom dead center when, as the curvature of the line indicates, the ports begin to move out of registration and at the point indicated at *b*, approximately twenty- 120 seven degrees past bottom dead center, the port 41 moves completely out of registration with the port 38, sealing the cylinder. The cylinder remains sealed during the next inward movement of the sleeve to top dead 125 center.

center, which is the compression stroke, and the sealed condition is maintained as the piston next moves outwardly, which is the power stroke, to the point indicated at *d*, approximately thirty-eight degrees before bottom dead center is reached, when the port 40 of the sleeve valve begins to move into registration with the port 36 of the cylinder. This registration rapidly becomes complete as shown by the curvature of the line and is maintained substantially full during the inward stroke of the sleeve valve, which is the exhaust stroke, and as the sleeve valve reaches top dead center the port 40 begins to move rapidly out of registration with the port 36 as indicated by the curvature of the line and is completely sealed at the point marked *e*, approximately seven degrees past top dead center. The cylinder remains sealed until the sleeve valve reaches approximately fifteen degrees past top dead center when the intake valve again begins to open as above described.

The valve setting may be varied and the points of opening and closing adjusted by changing the setting of the timing gears or the ratios of the connecting rods.

In a four cycle engine of four cylinders such as shown in the drawings the cycle of operations is substantially as illustrated in Fig. 3. Thus in the case of No. 1 cylinder the piston is on its firing stroke, the sleeve valve being turned into substantially its neutral position wherein both the ports 36 and 38 are sealed. In the case of No. 2 cylinder the piston is on its compression stroke and the sleeve valve is turned so that both the ports 36 and 38 are sealed. In the case of No. 3 cylinder the piston is on its scavenging or exhaust stroke and the sleeve valve has been turned to bring its port 40 in registry with the port 36 for the exhaust of the products of combustion. In the case of No. 4 cylinder the piston is on its suction or fuel-intake stroke and the sleeve valve has been turned to bring the port 41 in registration with the intake port 38.

It is apparent that a double seal is provided for the ports 36 and 38 when closed by the sleeve valve 14 working between the annular walls of the extension 8 of the cylinder head and the interior wall of the cylinder, thereby preventing the escape of compression from the firing chamber or the entrance of oil from the crank case into the firing chamber. Likewise the skirt 17 of the piston 18 is provided with a double seal between the liner 15 and the sleeve valve 14.

It is further evident that the sleeve valve and its liner are water cooled both from within and without, as is also the piston during the upper half of its path of movement.

It is further evident that the sleeve valve moves with the piston although at less speed,

thereby minimizing the friction and wear between the piston and the sleeve valve and decreasing the relative movement between the piston and the sleeve valve of the path of movement of the piston, and thereby reducing the friction and wear between the piston and the surface with which it is in sliding contact.

The fact that the sleeve valve is traveling in the same direction as is the piston during the oscillating movement of the former prevents the valve or the piston from losing its true cylindrical shape from wear as would occur were the relative movement of the part simply longitudinal.

The complete water jacketing of the firing chamber prevents the overheating of its walls and greatly increases its efficiency because of the ability thus afforded to use high compression without pre-ignition or overheating.

The position and the frustro-conical shape of the firing chamber 11 and the axial position of the spark plug relative to said firing chamber result in better flame propagation and more complete fuel combustion.

In Fig. 6 I have shown the piston 18 reverted as in common practice, and moving entirely within the sleeve valve. In Fig. 7 I have shown the firing chamber formed by the interior of the sleeve valve, the sleeve valve being thus water cooled from without only and lacking the double seal. I prefer however the structure shown in the first four views of the drawings.

In Fig. 8 I show the sleeve valve 14 provided with but a single valve port 42, the one port being used both for exhaust of the burned gases and for the admission of fuel, the sleeve valve being intermittently oscillated sufficiently to bring the port 42 into registration with either the cylinder exhaust port 36 or the cylinder fuel intake port 38, said ports being shown in Fig. 8 disposed forty-five degrees apart so as to reduce the arc of oscillation of the sleeve valve. It is evident that the ports 36 and 38 may be diametrically opposed, but this would require a longer arc of oscillating movement of the sleeve valve.

What I desire to claim is:—

1. In an internal combustion engine, the combination with a cylinder provided with fuel-inlet and exhaust ports, a sleeve valve working in said cylinder to control the operation of said ports, a piston working in said sleeve valve, a main crank shaft and connections between said main crank shaft and said sleeve valve and piston to reciprocate them, of a second shaft, and crank connections between said second shaft and said sleeve valve to impart oscillating motion to the sleeve valve.

2. In an internal combustion engine, the combination with a cylinder provided with fuel-inlet and exhaust ports, a sleeve valve

working in said cylinder to control the operation of said ports, a piston working in said sleeve valve, a main crank shaft and connections between said main crank shaft and said sleeve valve and piston to reciprocate them, of a second shaft rotated at half the speed of the main crank shaft, and crank connection between said second shaft and the sleeve valve to impart oscillating motion to the sleeve valve.

3. In an internal combustion engine, the combination with a cylinder provided with fuel-inlet and exhaust ports, a sleeve valve working in said cylinder to control the operation of said ports, a piston working in said sleeve valve, and a crank shaft, of a pair of throw cranks on said crank shaft disposed in parallelism, and connecting rods coupling said cranks to said piston and said sleeve valve respectively.

4. In an internal combustion engine, the combination with a cylinder provided with fuel-inlet and exhaust ports, a sleeve valve working in said cylinder to control the operation of said ports, a piston working in said sleeve valve and a crank shaft, of a pair of throw cranks on said crank shaft disposed in parallelism, and connecting rods coupling said cranks to said piston and said sleeve valve respectively, the sleeve valve crank having less throw than the piston crank.

5. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, and means for imparting oscillating movement to said sleeve valve.

6. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, and means for intermittently imparting oscillating movement to said sleeve valve.

7. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, a second shaft, and connections between said

second shaft and said sleeve valve to impart oscillating movement to said sleeve valve.

8. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, a second shaft, and connections between said second shaft and said sleeve valve to impart an intermittent oscillating movement to said sleeve valve.

9. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, a second shaft, and means connecting said second shaft to the connecting rod of said sleeve valve to impart oscillating movement to the latter.

10. In an internal combustion engine, the combination with a cylinder provided with fuel-inlet and exhaust ports, a sleeve valve working in said cylinder to control the operation of said ports, a piston working in said sleeve valve and a crank shaft, of a pair of parallel throw cranks on said crank shaft, connecting rods coupling said cranks to said piston and said sleeve valve respectively, a second shaft, and crank connection between the second shaft and the connecting rod of the sleeve valve to impart oscillating movement to the sleeve valve.

11. In an internal combustion engine, the combination with a cylinder provided with fuel-inlet and exhaust ports, a sleeve valve working in said cylinder to control the operation of said ports, a piston working in said sleeve valve, and a crank shaft, of a pair of parallel throw cranks on said crank shaft, connecting rods coupling said cranks to said piston and said sleeve valve respectively, a second shaft rotated at half the speed of the main crank shaft, and crank connection between the second shaft and the connecting rod of the sleeve valve to impart oscillating movement to the sleeve valve.

12. In an internal combustion engine, the combination with a cylinder having fuel-inlet and exhaust ports, a ported sleeve valve working in the cylinder to control said ports, a piston working in said sleeve valve and a crank shaft, of a pair of parallel cranks on said crank shaft, and connecting rods individually connecting said cranks with the sleeve valve and the piston whereby the pis-

ton and sleeve valve are caused to move always simultaneously and in the same direction, the throw of the sleeve valve crank being less than the throw of the piston crank.

5 13. In an internal combustion engine, the combination with a cylinder having fuel-inlet and exhaust ports, a ported sleeve valve working in the cylinder to control said ports, a piston working in said sleeve valve and a 10 crank shaft, of a pair of parallel cranks on said crank shaft, connecting rods individually connecting said cranks with the sleeve valve and the piston, and means for intermittently oscillating the sleeve valve 15 during its longitudinal movement.

14. In an internal combustion engine, the combination with a cylinder having fuel-inlet and exhaust ports, a ported sleeve valve working in the cylinder to control said ports, 20 a piston working in said sleeve valve and a crank shaft, of a pair of parallel cranks on said crank shaft, connecting rods individually connecting said cranks with the sleeve valve and the piston, the throw of the sleeve 25 valve crank being less than the throw of the piston crank, and means for intermittently oscillating the sleeve valve during its longitudinal movement.

15. In an internal combustion engine, the 30 combination with a cylinder having fuel-inlet and exhaust ports, a ported sleeve valve working in the cylinder to control said ports, a piston working in the sleeve valve and a main crank shaft, of parallel cranks on said 35 shaft, a connecting rod coupling said sleeve valve to one of said cranks, a second connecting rod coupling the piston and the other of said cranks, a second shaft, and a connecting rod coupling said second shaft to 40 the sleeve valve to impart oscillating movement to the sleeve valve.

16. In an internal combustion engine, the combination with a cylinder having fuel-inlet and exhaust ports, a ported sleeve valve 45 working in the cylinder to control said ports, a piston working in the sleeve valve and a main crank shaft, of parallel cranks on said shaft, a connecting rod coupling said sleeve valve to one of said cranks, a second connecting rod coupling the piston and the other of said cranks, a second shaft, and a connecting rod coupling said second shaft to 50 the sleeve valve to impart oscillating movement to the sleeve valve, said second shaft 55 being rotated at half the speed of the main crank shaft.

17. In an internal combustion engine, the combination with a cylinder having fuel-inlet and exhaust ports, a ported sleeve valve working in the cylinder to control said ports, 60 a piston working in the sleeve valve and a main crank shaft, of parallel cranks on said shaft, a connecting rod coupling said sleeve valve to one of said cranks, a second connecting rod coupling the piston and the other of 65 said cranks, a second shaft, and a connecting rod coupling said second shaft to the connecting rod of the sleeve valve to impart oscillating movement to the sleeve valve.

18. In an internal combustion engine having a cylinder, the combination of a sleeve valve working in said cylinder to control the fuel inlet and exhaust of said cylinder, an inverted piston working in said sleeve valve, 70 means for reciprocating said sleeve valve and 75 said piston simultaneously, and a double seal between the skirt of said piston and said sleeve valve.

19. In an internal combustion engine having a cylinder, the combination of a sleeve 80 valve working in said cylinder and arranged by its reciprocation and oscillation to control the fuel inlet and exhaust of said cylinder, an inverted piston working in said sleeve valve, 85 means for reciprocating said piston, means for reciprocating and oscillating said sleeve valve, and a double seal between the skirt of said piston and the sleeve valve.

20. In an internal combustion engine having a cylinder, the combination of a sleeve 90 valve working in said cylinder to control the fuel inlet and exhaust of said cylinder, an inverted piston working in said sleeve valve, 95 said sleeve valve being provided with an annular chamber in its walls wherein the skirt of said piston works, and means for reciprocating said sleeve valve and said piston.

21. In an internal combustion engine having a cylinder, the combination of a sleeve valve working in said cylinder and arranged 100 by its reciprocation and oscillation to control the fuel inlet and exhaust of said cylinder, an inverted piston working in said sleeve valve, 105 the sleeve valve being provided with an annular chamber in which the skirt of said piston works, means for reciprocating said piston, and means for reciprocating and oscillating said sleeve valve.

Signed at Pittsburgh, Pa., this 16th day of June, 1926.

JOSEPH E. WHITFIELD.
